[57] CLAIM

The ornamental design for a lamp, or the like, as shown and described.

DESCRIPTION

FIG. 1 is a front elevational view of a lamp showing my new design;

FIG. 2 is a left side elevational view thereof;

FIG. 3 is a sectional view taken along line 3—3 of FIG. 1;

FIG. 4 is a bottom view thereof;

FIG. 5 is a top plan view thereof;

FIG. 6 is a right side elevational view thereof;

FIG. 7 is a rear view thereof;

FIG. 8 is a perspective front view thereof.

The lamp envelope is shaded in the drawings to indicate contrast.
